UNITED STATES PATENT OFFICE

STUART PARMELEE MILLER, OF GLEN RIDGE, NEW JERSEY, ASSIGNOR TO THE BARRETT COMPANY, OF NEW YORK, N. Y., A CORPORATION OF NEW JERSEY

RECOVERY OF TAR ACIDS AND OTHER PRODUCTS

Application filed July 16, 1927. Serial No. 206,368.

This invention relates to the production of tar acids and other products from coal tar and from coal distillation gases.

In ordinary coke oven operation, the coke oven gases are cooled rapidly by the introduction of ammonia liquor, or ammonia liquor and tar, into the collector main, and the gases passing through the collector main are then cooled further in coolers or coolers to relatively low temperatures. This cooling of the gases results in the separation of coal tar, part of which is usually recovered from the collector main, and part from the coolers or condenser, and this tar is ordinarily subjected to distillation in tar stills for the production therefrom of distillate oils and pitch residues. The lighter of carbolic oil fraction produced by such distillation is then subjected to treatment to extract the phenols or tar acids therefrom. It is necessary to subject the tar to distillation before the tar acids can be extracted, because the presence of tarry constituents in the tar itself and in the tarry oils directly produced from the coke oven gases interfere with and prevent the extraction of tar acids from the tar or tarry oil.

The coal tar produced from the coke oven gases at the coke oven plant is commonly transported to tar distillation plants, more or less remotely situated, and there subjected to distillation in externally heated tar stills. This shipment or transportation of the tar requires handling and rehandling of the tar with incidental losses, as well as added expense of transportation, and the distillation of the tar results in decomposition of more or less of the oil constituents of the tar with reduction in yield of distillate oils and increase in amount of pitch residue, and in the carbon content of such residue.

The present invention eliminates the necessity of transportation of tar to a tar distillation plant, and eliminates or minimizes the losses of tar in handling and transportation and the decomposition of the oil constituents of the tar on distillation. It provides an improved method whereby tar acids can be directly recovered at the coke oven plant from tar and tarry oils, and also from coke

oven gases directly. The present invention provides not only for the recovery of tar acids at the coke oven plant, but also of various oils and pitches, and of ammonia in an advantageous manner.

According to the present invention, tar, or tarry oils, which are themselves directly produced by cooling and condensation from coal distillation gases, are subjected to distillation by bringing them into intimate contact with hot coal distillation gases, with resulting enrichment of the gases in tar acid oils and with the production of a pitch residue of low carbon content. The enriched gases resulting from such distillation are then subjected to a cleaning treatment to separate pitch particles therefrom at a sufficiently high temperature to leave tar acid oils in the form of vapor, and the resulting cleaned gases, freed from heavy tar and pitch constituents, are then cooled to condense therefrom oils rich in tar acids which are extracted for the recovery of tar acids therefrom. Naphthalene, as well as tar acids, can advantageously be recovered directly in a state of high purity from such oils.

When ordinary coke oven gases are cleaned with an electrical precipitator at a temperature sufficiently high to permit the gases to be passed through an ammonia saturator above the dew point of water, a large part of the vapors of carbolic oils will remain in the vapor state and can be condensed from the gases after the gases have passed through the saturator, and the tar acids extracted from the resulting oils, as described in my companion applications Serial Nos. 206,370 and 206,365. If the gases are cleaned at a higher temperature and cooled to separate oil therefrom at a temperature above the dew point of water and before passing the gases through the saturator at such temperature, the oil will be a relatively heavy oil, containing relatively small amounts of tar acids, mainly higher boiling tar acids, such oils being suitable for use directly as creosote oils, as described in my companion application Serial No. 206,365. In order to separate oils rich in tar acids from ordinary coke oven gases, the gases must be cooled to a lower temper-

ature, for example, around 25° to 35° C. and if such cooling precedes the passage of the gases through the ammonia saturator, water will be condensed from the gases along with the tar acid oils, and this water will contain ammonia, which must be recovered therefrom, e. g., by distillation. Processes by which tar acid oils are directly recovered from coke oven gases prior to passing the gases through the saturator at a low temperature, are described in my application Serial Nos. 202,736, 206,366 and 206,367.

The process of the present invention is an improvement upon the processes of my said companion applications, and involves distillation of tar or tarry oils to distill tar acid oils therefrom by direct contact with hot coal distillation gases, such as coke oven gases, and with resulting enrichment of the gases in such tar acid oils, before the gases are subjected to the cleaning operation for the removal of heavy tar and pitch constituents therefrom; and the enriched gases are then subjected to cooling for the separation of tar acid oils, or of both creosote oils and tar acid oils, before the gases are passed to the ammonia saturator.

Ordinary coke oven gases leave the individual coke ovens at a high temperature, around 600° to 700° C., or higher, and are commonly passed through uptake pipes leading from the individual ovens to a collector main common to a number of ovens. The heat which the coke oven gases contain is commonly dissipated by the introduction of a large amount of ammonia liquor, or of ammonia liquor and tar, into the gases in the collector main and in the pipes leading thereto, and by external cooling of the pipes through which the gases pass, and by subsequent cooling in the condenser. The heat contained in the hot coke oven gases from a single oven is many times that required to distill the amount of tar produced from the gases from such oven, while the gases from a battery of ovens, or from a group of ovens united to a single collector main, are capable of distilling an amount of tar many times that ordinarily produced from the battery, if the tar is brought into intimate contact with the gases, so that the heat of the gases is effectively utilized.

According to the present invention, the gases from a sufficient number of ovens are employed for distilling tar or tarry oils by introducing the tar or tarry oils directly into intimate contact with the gases while still at a high temperature, thereby distilling the tar or tarry oils and driving off tar acid oils therefrom. Such distillation of tar or tar acid oils by bringing them into intimate contact with the hot gases results in greatly enriching the gases in oil vapors, and particularly in tar acid oil vapors. For example, the content of oil vapors ordinarily carried by coke oven gases is only around one per cent,

whereas, by effective distillation of tar or tarry oils by bringing them into intimate contact with the hot coke oven gases at a sufficiently high temperature, the condensable vapor content of the gases can be radically increased to around ten per cent, or in some cases as high as fifteen or twenty per cent. This radical increase in vapor content of the gases makes necessary the cleaning of the enriched gases at a much higher temperature in order to maintain the tar acid oils in vapor form and to recover a high yield thereof, and make possible also the recovery of a large amount of tar acid oils at a temperature sufficiently high that the gases can thereafter be passed through the ammonia saturator at a temperature above the dew point of water. Accordingly, in the improved process of the present invention, the enriched gases resulting from the distillation of the tar or tarry oil therein, are subjected to a cleaning treatment at a high temperature, sufficient to maintain the desired tar acid oils in the form of vapors, while separating a pitch of higher or lower melting point therefrom, and the resulting gases carrying tar acid oil vapors are then subjected to cooling and condensation to separate an oil rich in tar acids, from which the tar acids can be directly and advantageously extracted. Where the maximum yield of tar acid oils is to be collected in a single condenser, the gases can be cooled to a low temperature, around 25° to 35° C., before passing them to the ammonia absorber or saturator; but a large proportion of the tar acid oils can be recovered at a temperature above the dew point of water, and the gases can then be passed to the ammonia absorber or saturator above the dew point of water, with subsequent further cooling of the gases to separate additional amounts of light tar acid oils therefrom, prior to the final scrubbing of the gases to recover coke oven light oils e. g., benzol, toluol, etc. therefrom.

The tar or tarry oil to be distilled, according to the present process, may be ordinary coal tar, comprising the total tar constituent recovered from coke oven gases, or may be a heavy tar such as is separated in the collector main of an ordinary coke oven plant, or it may be the tarry oil separated from the gases in the coolers or condensers of the ordinary coke oven by-product system. Where the only tar available to be distilled is that produced at the coke oven plant, only a few of the ovens are required to supply the gas for distilling the tar from the remainder of the battery. In such cases, gases from the greater part of the battery can be condensed and cooled in the ordinary manner for the separation of heavy tar and tarry oils therefrom, and the gases from a few only of the ovens employed for the distillation of the tar. Where tar is produced by a large number of batteries, the gases from a single bat-

terry may be employed for the distillation, or part of the gases of the battery, for example, the gases collected in a single collector main. Tar from an outside source, such as another coke oven plant, or from gas retorts (horizontal, vertical or inclined) or low temperature carbonization tar, rich in tar acids, can be subjected to distillation, according to the present invention, and the resulting enriched gases treated for the direct recovery of tar acid oils therefrom. Instead of using the total tar from the battery, only the lighter tar or tarry oils, such as are commonly thrown down in the coolers or condensers of a by-product system, can be employed. These tarry oils are rich in tar acids and naphthalene, and, by distilling them in the hot coal distillation gases, a very great enrichment of the gases in tar acid oil vapors and in naphthalene may be obtained.

The distillation of the tar or tarry oil in direct contact with the hot coke oven gases can be carried out, for example, as described in my prior applications, Serial Nos. 166,081, 25 172,962, 179,209, 158,137, 181,366, 197,029, or 171,955. For example, the tar or tarry oil can be sprayed or otherwise introduced into intimate contact with the hot coke oven gases in an ordinary collector main, or in a short 30 collector main, or in other form of still in which the tar or tarry oil is brought into intimate contact with the hot coke oven gases.

The distillation of the tar or tarry oil results in the production of a pitch residue and, 35 depending upon the extent to which the distillation is carried, a hard or high melting point pitch can be produced, or a softer and lower melting point pitch. So also, the extent to which the distillation is carried will 40 determine the character of the vapors which are distilled from the tar or tarry oil, and which enrich the gases employed for the distillation. Where the distillation is carried up to an extent such that a high melting pitch 45 is produced, considerable enrichment of the gases in heavier oil constituents will take place. By limiting the distillation, however, a much greater enrichment of the gases in lighter oil vapors can be obtained, particularly 50 in oil vapors rich in tar acids or naphthalene, but particularly so when the tarry oils, rich in tar acids and naphthalene, such as are 55 condensed in the ordinary condensers of a by-product recovery system, are subjected to regulated distillation.

Depending upon the temperature at which the cleaning of the enriched gases takes place, there may be condensed from the cleaned gases only a tar acid oil, or there may be condensed both a creosote oil at a higher temperature and a tar acid oil at a lower temperature. Where only a tar acid oil is to be directly recovered, the enriched gases can be treated at a temperature such that a low 60 melting point pitch, for example, having a

melting point around 105° F., is separated therefrom, suitable for use directly for road construction purposes, while leaving a large amount of tar acid oils in vapor form. The temperature at which the cleaning of the 70 gases and the separation of the pitch particles therefrom is effected, will vary with the extent of the enrichment, but will be considerably higher than the temperature at which ordinary coke oven gases will yield a pitch 75 of similar melting point. Whereas, for example, with ordinary coke oven gases, where a temperature of only around 110° to 120° C. will give a pitch of melting point around 105° to 110° F., with enriched gases, greatly 80 enriched in tar acid oil vapors, a much higher temperature, around 140° to 150° C. or higher may be required. By subjecting the gases at such temperature to the action of an electrical precipitator, a valuable low melting 85 point pitch can be directly produced and tar acid oils can be subsequently condensed from the cleaned gases and extracted for the recovery of tar acids therefrom.

Where both creosote oils and tar acid oils 90 are to be successively condensed from the cleaned enriched or unenriched gases, a much higher temperature is required for the cleaning operation. For example, a pitch of melting point around 300° F. can be separated 95 from the gases when the cleaning operation is carried out at a temperature around e. g. 320° C. depending upon the extent of the enrichment of the gases. The distillation of tar with the hot coke oven gases can be carried 100 to an extent which will give even a higher melting point pitch, for example, having a melting point around 400° F., or higher, with passage of the resulting enriched gases through the electrical precipitator at the 105 same temperature, or at a regulated lower temperature, which will give a lower melting point pitch from the precipitator, while leaving in the gases a large amount of oil vapors. The enriched gases can then be condensed 110 first, to separate creosote oils therefrom; for example, at a temperature of about 150° C., and subsequently further condensed to separate carbolic or tar acid oils therefrom, either by cooling to a temperature around 25° to 35° 115 C., in the carbolic oil condensers, or by limiting the cooling so that the gases leave the cooler or condenser while still at a temperature above the dew point of water, such that they can be passed to the ammonia saturator 120 at a temperature above the dew point of water. When the tar acid oil is condensed from the enriched gases at a temperature above the dew point of water, the present invention provides an advantageous method of 125 recovering ammonia directly from the enriched gases by passing them through an ammonia absorber or saturator at a temperature above the dew point of water, such that the ammonia is recovered from the gases 130

without dilution by condensed water. Such direct recovery of ammonia from the gases above the dew point of water will still leave some of the lighter carbolic oils in the vapor form, and these oils can be subsequently condensed and recovered by subjecting the gases leaving the separator first to cooling to a temperature around 25° to 30° C., to separate additional carbolic oil, and then passing the gases to the scrubber or absorber for the coke oven light oils. In such case, the recovery of tar acid oils will be a two-stage recovery process, the greater part of the tar acid oils being condensed and recovered before the gases pass through the ammonia saturator, and a further amount of light carbolic oils being recovered after the gases pass through the ammonia saturator.

Where the advantages incident to the direct recovery of ammonia above the dew point of water are not to be obtained, the entire carbolic or tar acid oil can be recovered in a single operation by cooling the gases at once to a temperature around 25° to 35° C., and separating the condensed tar acid oil therefrom, and then passing the gases either with or without reheating, to the ammonia acid absorber, or without reheating to the ordinary water absorber, and finally to the scrubber or absorber for the coke oven light oils.

The operation of the present process can advantageously be carried out with circulation of hot tar or pitch through the collector main or through a small collector main, and with spraying of tar or pitch into the collector main with resulting distillation of the tar or pitch and enrichment of the coke oven gases in vapor content resulting from the distillation. Instead of using tar or pitch, the light tar or tarry oil from the condensers of the ordinary by-product recovery system can advantageously be employed and distilled sufficiently to remove therefrom the greater part or all of the tar acid oils together with naphthalene, leaving a pitch residue of higher or lower melting point. By operating in this way, a pitch product can be directly produced in the collector main, and another pitch product can be separated in the electrical precipitator, which may be kept separate, or which may be refluxed back and admixed with the pitch product from the collector main. Thereafter the enriched gases, cleaned in the electrical precipitator, and still containing a large amount of tar acid oil vapors, are subjected to cooling and condensation for the separation of a tar acid oil therefrom, which is extracted for the recovery of tar acids. Depending upon the temperature of the collector main operation and of the electrical precipitator, the cleaned gases may contain only the tar acid oil vapors, or they may contain in addition heavier creosote oil vapors, which can be subse-

quently condensed as a creosote oil prior to the condensation of the tar acid oil from the vapors at a lower temperature. Because of the very great enrichment of the gases in oil vapors, a greatly increased yield of clean oils can be directly obtained, and the carbolic oils can be obtained in large part at a temperature above the dew point of water, so that the gases after the separation of such carbolic oil can then be passed directly to the saturator at a temperature above the dew point of water, where this is desired.

The extraction of the tar acids or phenols from the carbolic or tar acid oils recovered in the present process before the gases pass through the ammonia saturator, may be, for example, with a solution of caustic alkali, such as ten percent caustic soda solution, which will combine with the tar acids to form the sodium salts thereof, and by separation of the resulting carbolate solution from the extracted oil. The carbolate solution can then be treated to decompose the sodium salts and set free the phenols or tar acids, for example, by treatment with carbon dioxide to set free most of the tar acids, and by adding a small amount of sulphuric acid to the separated tar acids to complete the setting free of the tar acids from the small amount of carbolate solution still remaining dissolved in the separated tar acids. The tar acids so extracted and separated may then be further refined by distillation, if desired, to separate them into refined commercial products. The extracted oil, from which the tar acids have been extracted, can be employed for solvent purposes or as a lamp black oil, or it can be blended with pitch to form a fuel product, such as described in my companion application Serial No. 206,369 which has matured into Patent No. 1,811,953.

The invention will be further described in connection with the apparatus illustrated, in a more or less conventional and diagrammatic manner in the accompanying drawings which show a coke oven plant by-product recovery system adapted for the practice of the process of the invention.

In the accompanying drawings,

Fig. 1 is a plan view of a portion of a coke oven plant and by-product recovery system adapted for the practice of the invention;

Fig. 2 is an enlarged section of the electrical precipitator and collector main;

Fig. 3 is an enlarged view of one form of tar acid extracting apparatus;

Fig. 4 is a sectional elevation of the electrical precipitator; and

Fig. 5 shows one form of condenser. The apparatus illustrated in the drawings comprises part of a coke oven battery, 5, the individual ovens of which have individual uptake pipes and goose-necks 6 leading to a collector main 7, having a center box 8, and

which collector main may be the ordinary collector main common to a considerable number of ovens, or a short collector main common to only a few ovens, depending upon the amount of tar or tarry oils to be distilled therein.

Tar or tarry oil is supplied to the collector main and goose-necks, through spray nozzles 9 and 9' therein, from the pipe 10, connected to a suitable source of tar or tarry oil. The introduction of the tar or tarry oil into intimate contact with the hot gases entering and passing through the collector mains will result in distillation of the tar or tarry oil and the production of a pitch residue of higher or lower melting point, and the enrichment of the gases in the oil vapors produced by the distillation. The pitch residue will escape from the collector main through the center box 8, and the outlet pipe 11, to the receptacle 12, and forms one of the products of the process which can be kept separate, or which can be admixed with the pitch from the electrical precipitator.

The enriched gases leaving the collector main are conducted through a pipe 14, to an electrical precipitator 15, preferably closely adjacent to the collector main in order that the temperature of the gases may not be reduced to any considerable extent between the collector main and the precipitator. The precipitator may be of any suitable form of construction. As shown it consists of a shell enclosing a number of tubes 15' supported in heads 16 and 17 within the shell. An inlet 18 near the bottom communicates with a chamber 19, which is partially separated from the tube section by a baffle 20. An outlet 21, permits the escape of the cleaned gases from the separator. A plurality of electrodes, 22, in the form of metal rods, extends through the tubes 15' and is supported from a bus bar 23, located near the upper ends of the tubes. The bus bar extends at both ends into casings 24, which enclose insulators 25, upon which the bus bar is supported. The high tension current line extends into one of the casings 24 and connects with the bus bar 23, thus supplying the necessary current from any suitable source of uni-directional current of high tension. The casing of the separator is grounded or otherwise connected to the source of current to complete the circuit. The casing and tubes form the positive electrode, the electrodes connected to the bus bar being negative. The form and arrangement of the bus bars in the circuit can be varied. The arrangement should be such as to supply high tension uni-directional current to the electrodes, thereby permitting a continuous discharge between the electrodes and the tubes through which the gases pass.

The gases from the collector main enter the electrical precipitator carrying in suspension particles of pitch which are separated in the

electrical precipitator with the result that the pitch product collects in the bottom of the separator and runs out through the pipe 25' to a pitch receptacle, while the gases freed from pitch particles, and still containing tar acid oil vapors, escape through the cross-over main 26 to the condensing system. The condensing system shown includes only a single condenser 27, of a construction illustrated in Fig. 5, and provides for the recovery of a tar acid oil fraction without provision for also recovering a higher creosote oil fraction. The condenser shown is an indirect condenser comprising tubes 28 through which the gases pass in heat exchange relation with a cooling liquid such as water, which is circulated through a casing 29, surrounding the tubes. The gases enter the condenser through the cross-over main 26, and escape therefrom through the gas outlet pipe 32. The tar acid oil condensed in the condenser is withdrawn through the outlet pipe 30, to the receptacle 31.

From the condensers the gases pass through the exhauster 33, and then through the ammonia saturator 34, and thence to the scrubber or absorber for coke oven light oils (not shown). Where the maximum yield of tar acid oils is to be recovered in the condenser 27, the temperature of the gases may be lowered to 25° to 35° C., and thereafter passed, either without or with reheating, to the ammonia absorber. Instead of recovering the maximum amount of tar acid oils in this way by a single condensation treatment of the gases, they may advantageously be cooled only to a temperature around 80° to 100° C., and then passed to the ammonia absorber or saturator, while still above the dew point of water and the ammonia recovered therefrom without condensation of water, and the gases thereafter subjected to further cooling for the recovery of additional amounts of light carbolic oil before they pass to the final scrubber for the coke oven light oils.

The tar acid oil condensed in the condenser 27, and collected in the receptacle 31, can be freed from any accompanying ammonia liquor, in case the condensation is carried out at a sufficiently low temperature to condense ammonia liquor with the oil, and the ammonia liquor can be collected in the receptacle 31 and the oil in the receptacle 35. This oil is then subjected to extraction in the extraction apparatus 36, which is shown as comprising a tank having suitable agitating means, 37, therein. The extracting agent, for example, a ten percent solution of caustic soda, can be added in suitable proportion to the tank through an inlet 38, and mingled with the oil by agitation until the extraction is completed. The neutral or extracted oil can then be returned through a pipe 39, and the carbolic solution comprising the combined tar acids and alkali solution, can be

withdrawn through an outlet 40, and can be treated for the liberation and recovery of tar acids, for example, by treatment with carbon dioxide to form sodium carbonate in solution and to separate the tar acids which can be further refined or distilled to form refined commercial products.

This distillation of tar or tarry oils in accordance with the present invention results in a very great enrichment of the gases, particularly where the distillation of the tar or tarry oil is carried only to the extent of removing lighter oils rich in tar acid therefrom, and leaving relatively low melting point pitch residues, for example, pitch residues melting around 105° F. When the resulting gases greatly enriched in such tar acid oil vapors, are cleaned at a sufficiently high temperature to separate the pitch particles therefrom and to leave the tar acid oils in vapor form, and the resulting cleaned oils are then condensed, the condensation treatment can be regulated to give directly an oil rich in tar acids, which can advantageously be extracted for the recovery of tar acids therefrom. Such oils may also be rich in naphthalene, in which case the extraction of the tar acid should be carried out at a sufficiently high temperature to keep the naphthalene in a liquid state and prevent its crystallization during the extraction process. In many cases the naphthalene will be present in sufficient amount so that by cooling and chilling the oil before the extraction of tar acids, a considerable amount of naphthalene can be crystallized therefrom, and filtered off from the oil, leaving an oil still further enriched in tar acids, which can advantageously be extracted to separate the tar acids therefrom. When the naphthalene is not separated from the oil before its extraction to remove tar acids, the removal of tar acids at a temperature above that of crystallization of the naphthalene will leave an extracted oil, from which naphthalene can advantageously be recovered by cooling and chilling to produce crystallization. Naphthalene of high purity can be directly recovered from the oils as well as tar acids, and both the tar acids and the naphthalene can be recovered in large amounts, due to the large volume of tar acid oils which can be directly produced by the distillation of tar or tarry oils in the manner described.

The process of the present invention is an advantageous process for effecting a limited distillation of tar or tarry oils to separate therefrom only the lighter tar acid oils while leaving the heavier oils behind in the pitch residue, where this residue is desired, for example, for fuel purposes, but where a tar acid oil is desired, from which tar acids can be extracted, or tar acids and naphthalene. The neutral oil after the separation of the tar acids, or of the tar acids and naphthalene,

can be returned to the pitch residue and blended therewith to form a composite fuel product, where such a product is desired.

The process of the present application is an improvement upon the processes of my prior applications, Serial Nos. 202,736, 206,366, 206,367, 206,365, and 206,370, in that it involves the distillation of tar or tarry oil with hot coke oven gases to enrich the gases in tar and oil constituents and the subsequent direct recovery from the enriched gases, after cleaning to separate pitch therefrom, of a tar acid oil, which is made up in large part of the distillate oil from the distillation of the tar or tarry oil, and in part from the tar acid oil directly recovered from the gases employed for the distillation. The present process, accordingly, provides for the recovery of tar acid oils in part by distillation, and in part directly from the hot coke oven gases employed for the distillation with advantageous utilization of the heat of the gases for effecting the distillation and for simultaneous recovery of tar acid oils from the distilled vapors and from the coke oven gases, all this distillation being accomplished with substantially less decomposition than is the case in ordinary distillation processes.

References to pitch melting points refer to melting points determined according to the method described in "Methods of Analysis Used in the Coal Tar Industry" by J. M. Weiss. The Journal of Industrial and Engineering Chemistry, Vol. 10, No. 10, October 1918, page 817.

I claim:

1. The method of recovering tar acids, which comprises bringing tar-acid-containing oils or tars into intimate contact with hot coal distillation gases at a temperature sufficient to vaporize such oils and to enrich the gases in such oil vapors, subjecting the enriched gases to a cleaning operation to remove heavy tar and pitch constituents therefrom at a sufficiently high temperature to leave tar acid oils in the form of vapors, cooling the enriched gases to separate tar acid oil therefrom, and extracting tar acids from such oil.

2. The method of producing tar acids, which comprises bringing tar or tarry oils into intimate contact with hot coke oven gases at a sufficient temperature to distill tar acid oils therefrom and to enrich the gases employed for the distillation in such oil vapors and to produce a pitch residue from the distillation, subjecting the resulting enriched gases to cleaning with an electrical precipitator at a sufficiently high temperature to remove pitch from the gases and to leave tar acid oils in vapor form, subsequently cooling the cleaned gases to separate a tar acid oil therefrom and extracting tar acids from such oil.

3. The method of producing tar acids and creosote oils, which comprises subjecting tar to intimate contact with hot coke oven gases to distill the tar and produce a pitch residue and enriched gases containing creosote and tar acid oil vapors, subjecting the resulting enriched gases to cleaning with an electrical precipitator at a sufficiently high temperature to leave creosote oil and tar acid oil vapors therein; cooling the resulting cleaned gases so as to separate a creosote oil therefrom and subsequently further cooling the gases to separate a tar acid oil therefrom before passing the gases through an ammonia saturator, and extracting tar acids from the tar acid oil.

4. The method of treating coke oven gases, which comprises enriching hot coke oven gases at a high temperature by distillation of tar or oil therewith, passing the enriched gases while still at a sufficiently high temperature to maintain creosote oils in the form of vapor through an electrical precipitator to separate pitch from the gases, and cooling the resulting gases to a temperature sufficient to remove creosote oil therefrom before passing the gases through an ammonia absorber, the temperature to which the gases are cooled to remove creosote oil therefrom being such that the gases are left at a temperature above the dew point of the gases for water.

5. The method of treating coke oven gases, which comprises distilling tar or tarry oils by intimate contact with hot coke oven gases after the gases leave the coke ovens and before they have been cooled to a low temperature, subjecting the resulting enriched gases, containing vapors from the distillation, to the action of an electrical precipitator at a sufficiently high temperature to separate pitch therefrom and leave tar acid oils in the form of vapors, and cooling the resulting gases into separate tar acid oils therefrom before passing the gases thru an ammonia absorber, the temperature to which the gases are cooled to remove said tar acid oils being above the dewpoint of the gases for water.

6. The improvement in the process of claim 5 in which the gases, after leaving the saturator at a temperature above the dew point of water, are further cooled to separate a further amount of light tar acid oil therefrom and subsequently subjected to scrubbing for the recovery of coke oven light oils.

55 In testimony whereof I affix my signature.
STUART PARMELEE MILLER.
